CLAIM

The ornamental design for a cosmetic skin care tablet as shown and described.

DESCRIPTION

FIG. 1 is a perspective view of a cosmetic skin care tablet showing a first embodiment of my new design;

FIG. 2 is a front view thereof;

FIG. 3 is a back view thereof, being a mirror image of the front view;

FIG. 4 is a left side view thereof;

FIG. 5 is a ride side view thereof, being a mirror image of the left side view;

FIG. 6 is a top view thereof;

FIG. 7 is a bottom view thereof;

FIG. 8 is a perspective view of the cosmetic skin care tablet showing a second embodiment of my new design;

FIG. 9 is a front view thereof;

FIG. 10 is a back view thereof, being a mirror image of the front view;

FIG. 11 is a left side view thereof;

FIG. 12 is a ride side view thereof, being a mirror image of the left side view;

FIG. 13 is a top view thereof; and,

FIG. 14 is a bottom view thereof.

The thin, black lines shown with intermittent breaks are shading and/or tangent lines to show contour of the surfaces or curved edges, and do not actually appear on the surface of the cosmetic skin care tablet.

The stippling showing in FIGS. 8-14 depicts a fine, rough surface texture.
